(57) **CLAIM**

The ornamental design for an arm tucking device, as shown and described.

DESCRIPTION

FIG. 1 is a perspective view of the arm tucking device showing my new design;

FIG. 2 is another perspective view thereof;

FIG. 3 is a left side elevation view thereof;

FIG. 4 is a front elevation view thereof;

FIG. 5 is a right side elevation view thereof;

FIG. 6 is a rear elevation view thereof;

FIG. 7 is a top plan view thereof; and,

FIG. 8 is a bottom plan view thereof.

The broken line showing of environmental structure in the form of a mounting bracket in FIGS. 1-8 is for illustrative purposes only and forms no part of the claimed design.
